UNITED STATES PATENT OFFICE

135,338

DESIGN FOR A REED FOR MUSICAL INSTRUMENTS

Elver J. Fitchhorn, Delaware, Ohio

Application January 27, 1943, Serial No. 109,354

Term of patent 14 years

To all whom it may concern:

Be it known that I, Elver J. Fitchhorn, a citizen of the United States, residing at Delaware, in the county of Delaware and State of Ohio, have invented a new, original, and ornamental Design for a Reed for Musical Instruments, of which the following is a specification, reference being had to the accompanying drawing, forming a part thereof.

Fig. 1 is a perspective view of a reed for musical instruments, showing my new design;

Fig. 2 is an enlarged fragmentary elevational view of the vibratory end of the reed;

Fig. 3 is an enlarged transverse sectional view on the line III—III of Fig. 2.

I claim:

The ornamental design for a reed for musical instruments, as shown.

ELVER J. FITCHHORN.
